UNITED STATES PATENT OFFICE.

EMIL MUNDORF, OF AACHEN, GERMANY.

WASHING, FULLING, AND DYEING OF FABRICS.

Application filed May 6, 1925, Serial No. 28,491, and in Germany May 20, 1924.

Hitherto, the washing, fulling and dyeing of ordinary fabrics with rectangularly crossing warp and weft threads is mainly carried out in the form of ropes in which the fabric lists are open or sewn together. In these ropes the warp threads of the fabric extend in the longitudinal direction and the weft threads in the transverse direction. Therefore the mechanical action exerted, for instance during the washing of woolen fabrics, on the warp threads is entirely different from that exerted on the weft threads. The former are held stretched by the load of the rope and the pressure of the cylinders of the washing and fulling mills so that they do not shrink at all or only little but often lengthen even, while the weft threads lose about 10 to 20 per cent of their length. Owing to this unequal relaxation of the warp and weft threads the woolen fabrics produced are of mean quality; they will soon be worn out and lose their smooth form and good fit in wearing and mostly are liable to crumple and difficult to iron.

These drawbacks are avoided according to the invention by treating the fabric in the form of a tube-like rope which is produced by winding the fabric helically and in which the warp and weft threads extend at an acute angle with relation to the direction in which the fabric is drawn or moved during the washing, fulling and dyeing.

In treating a fabric rope according to the invention a much better degree of finishing will be attained than has hitherto been possible, because the influence of the finishing process on the two systems of threads is more uniform. The invention will now be

described with reference to the accompanying drawings in which:

Fig. 1 shows a fabric flattened into rope form.

Fig. 2 is a view showing the fabric in folded condition in which it is maintained during the wet treatment.

Instead of folding the fabric *a* into a rope in the direction of the warp threads, it is according to the invention wound helically into a tube-like rope as shown in Fig. 1. The lists *b* of the fabric abutting each other and extending along a helical line are sewn together before the fabric is drawn off the forming structure. The lists *b* are indicated in Fig. 1 by thick lines.

Having thus described my invention, what I claim as new and desire to secure by Letters-Patent, is:

1. The herein described method of preparing fabrics for washing, fulling, and dyeing, consisting in winding the fabric helically and securing it in such wound condition so as to produce a rope in which the warp and weft threads extend at an acute angle to the length of the rope.

2. The herein described method of preparing fabrics for washing, fulling and dyeing, which consists in winding the fabric helically with its lists abutting each other to produce a fabric rope in which the warp and weft threads are inclined to the longitudinal direction of the rope, and securing the abutting lists together.

In testimony whereof I have signed my name to this specification.

EMIL MUNDORF.
